UNITED STATES PATENT OFFICE.

WILLIAM H. BILBROUGH, OF ELMIRA HEIGHTS, NEW YORK.

UNION SUIT.

1,103,255.

Specification of Letters Patent. Patented July 14, 1914.

Application filed November 18, 1909. Serial No. 523,651.

To all whom it may concern:

Be it known that I, WILLIAM H. BILBROUGH, a citizen of the United States, residing at Elmira Heights, in the county of Chemung and State of New York, have invented certain new and useful Improvements in Union Suits, of which the following is a specification.

This invention relates to improvements in under-garments otherwise known as union suits; and my object is to provide a construction of the rear flaps and crotch gussets whereby these portions of the garment will be maintained in close fitting overlapped condition without the employment of buttons or other fastening means, and whereby said portions will be rendered elastic in the right direction to give freedom of motion and comfort to the wearer.

I attain my object by constructing the garments in the manner illustrated in the accompanying drawings, in which—

Figure 1 shows one of the flap portions as cut ready to apply to the garment; Fig. 2, a rear view of a union suit, showing the flaps as applied thereto; and Fig. 3, a front view of the same.

Like letters of reference designate like parts in the several views.

As is usual, the body and leg portions of this union suit are in one piece, cut from tubular knitted goods, with the wales running longitudinally from top to bottom. The two flap portions, A and A' are cut in the shape shown in Fig. 1, from the same knitted materials, with the wales, however, running preferably diagonally, as shown in the several figures. The body portion of the garment at the back is cut from the crotch to the waist line and the flaps A and A' are sewed in along this cut on the lines a b and a' b', to hang in opposite positions across the back of the garment. The flap A is sewed in at the waist line along the line a c, at the outside of the garment, while the flap A' is sewed along the same line extended at the inside of the garment from a' to c'. At their lower ends the flaps are cut on a convex curve b d, these curved ends being brought around to the front and sewed in to the leg portions along the lines b d, and b' d', as shown more clearly in Fig. 3. By reason of the convex ends, the flaps, where united to these front gusset seams b d and b' d', provide a fullness at each side of the crotch line which is adapted

to serve as a suspensory. This fullness also insures the closing of the crotch opening and the comfort of the wearer at this point, the inside flap being turned up inside of the outside flap, as shown more clearly by the broken lines in Fig. 3. By cutting the flaps with their longitudinal edges substantially parallel, or slightly broader at the bottom than at the top, there will be a broad overlap at each side of the back opening and around the crotch opening, thus insuring a complete closing of these openings in any position of the wearer of the garment. Along the line c d, and c' d', the two flaps are left free, being folded over on the broken line shown in Fig. 1, to form a hem, which is sewed with an elastic stitching, whereby these free edges of the flaps will be rendered longitudinally elastic.

In order to provide for the longitudinal stretching of the flaps, under the motions of the wearer, the wales may be run transversely, or, in other words, at right angles to the wales of the body of the garment. I prefer, however, to so cut the flaps that the wales will run diagonally, for the reason that, where the wales are run horizontally across the flaps, a permanent set is apt to be produced by reason of the stretching motions, which renders the flaps loose and baggy. By running the wales diagonally, however, in a direction oblique to the horizontal, this tendency to permanent set is counteracted, for the reason that the lines of elasticity do not coincide with the lines of pull produced by the motions of the body. What I claim as my invention and desire to secure by Letters Patent is—

1. A garment having a central longitudinal slit in the back thereof, said slit extending a short distance down the inner side of one of the leg portions, an elongated four-sided flap having one of its longitudinal edges secured along one edge of said slit, and its other longitudinal edge free, and having its upper edge secured across the back of the garment, and its lower edge convexly curved and secured along the front edge of the slit in the leg portion of the garment, whereby the free edge of said flap extends from the point of attachment of the upper edge to the front edge of the slit in the leg portion.

2. A union suit comprising united leg and body portions formed from a tubular knitted fabric, the body portion being slit at

the back from the waist line to the crotch, in combination with two oppositely disposed rear flaps, cut broader at the bottom than at the top, the upper ends of said flaps being united to the body portion along the waist line in overlapping arrangement, the remote longitudinal edges of the flaps being free, the adjacent edges being united to the correspondingly opposite edges of the slit in the body portion, and the lower ends of the flaps being cut convexly and united

to the leg portions along the front gusset seams, whereby a fullness is produced in both leg portions at the crotch, as and for the purpose described.

In testimony whereof I have affixed my signature, in presence of two witnesses.

WM. H. BILBROUGH.
